PISTON

Owen H. Fowler, Detroit, Mich., assignor to Hydraulic Brake Company, Detroit, Mich., a corporation of California

Original application March 7, 1940, Serial No. 322,790. Divided and this application January 10, 1941, Serial No. 374,095

17 Claims. (Cl. 309—4)

This invention relates to improvements in pistons for fluid pressure producing devices.

This application is a division of my pending application, Serial No. 322,790, filed March 7, 1940, and is made in accordance with the United States Patent Office Rule No. 42.

The invention is shown as embodied in a high pressure piston in a fluid pressure producing device of the two phase type, as, for example, the master cylinder in hydraulic brake mechanism. The piston embodying the invention is constructed to produce an effective seal within the high pressure chamber, and, further, it separates the high pressure chamber within the cylinder from the low pressure chamber therein and also permits flow of liquid under pressure from the low pressure chamber into the high pressure chamber.

An object of the invention is to provide a piston constructed to withstand high pressures and to effectively seal in a chamber complementary thereto.

One object of the invention is the provision of a piston having improved means on its head yieldable under high pressure to effectively inhibit the passage of fluid past the piston.

Another object of the invention is to provide a piston having a yieldable washer on its head, a pressure block thereon, and a sealing cup on the block effective under high pressure to cooperate and form an effective seal.

Another object of the invention is to provide a piston, including a head having thereon a rubber washer of high durometer reading, a pressure block having a convex face seated upon a complementary face on the washer, and a flexible sealing cup on the pressure block operative to function as a unit to establish an effective high pressure seal.

Other objects and advantages of the invention will appear from the following description taken in connection with the accompanying drawing forming a part of this specification, and in which—

Fig. 1 is a vertical sectional view of the fluid pressure producing device;

Fig. 2 is an enlarged sectional view illustrating one form of the high pressure piston;

Fig. 3 is a sectional view on line 3—3, Fig. 2;

Fig. 4 is a sectional view illustrating a modification of the piston;

Fig. 5 is a schematic diagram of a fluid pressure system embodying the fluid pressure producing device; and

Fig. 6 is an enlarged sectional view of the high pressure piston illustrated in Figs. 1 and 2.

Referring to the drawing for more specific details of the construction in which the invention is embodied, there is a single casting including a reservoir 10 having a filling opening 12 normally closed as by a head 14 having openings 16 therethrough for venting the reservoir to the atmosphere, and a cylinder 18 at the base of the reservoir having one of its ends closed as by a head 20 provided with a discharge port 22 and its other end open. In the open end of the cylinder is a chamber 24 of standard gauge, bearingized, and provided with spaced ports 26 and 28 affording communications between the chamber 24 and the reservoir 10. The cylinder 18 also has a bore 30, preferably of slightly less diameter than the chamber 24 arranged forward of, concentric to, and in direct communication with the chamber 24 and also with the discharge port 22.

A cylinder section 32 fitted tightly and sealed in the bore 30 has a bearingized chamber 34 and a circumferentially reduced portion providing in conjunction with the wall defining the bore 30 an annular passage 36 communicating with the chamber 24, and a port 38 arranged in the wall of the cylinder 32 provides a communication between the chamber 34 and the annular passage 36.

A piston 40 reciprocable in the chamber 24 is retained against displacement by a washer 42 seated on the annular shoulder in the open end of the cylinder 18 and held in place by a retaining ring 44 seated in a groove in the wall of the cylinder. The piston 40 includes a head 46, a body 48 having a reduced diameter providing in conjunction with the wall of the cylinder 18 an annular chamber 50 communicating with the reservoir 10 as by way of the port 26, and a skirt 52 supporting a sealing cup 54 for inhibiting seepage of fluid from the annular chamber 50 past the piston. The head 46 has a plurality of spaced passages 56 therethrough providing communications between the annular chamber 50 and that portion of the chamber 24 forward of the piston, and a sealing cup 58 seated on the head 46 of the piston controls the passages 56.

A washer 60 seated on the end of the cylinder 32 opposite the piston 40 has in its periphery a plurality of spaced notches 62 for the passage of fluid between the chamber 24 and the annular chamber 36, and also a plurality of spaced lands 64 preferably stamped or embossed in the body 55 of the washer, and a spring 66 interposed be-

tween the sealing cup 58 and the washer 60 serves to retain the cup and washer against displacement and also to assist in return of the piston 40 to its retracted position.

The piston 40 has disposed concentrically in its body 48 a valve chamber 68 opening through the head of the piston. This valve chamber has a port 70 providing a communication between the valve chamber and the annular chamber 50, and also a vent 72 opening from adjacent the bottom of the valve chamber into the annular chamber 50 for inhibiting fluid lock. A valve 74 slidable in the valve chamber abuts a compression spring 76 of high elasticity seated on the bottom of the valve chamber.

The valve includes a cylindrical body 78 fitted snugly for reciprocation in the valve chamber. This cylindrical body has a peripheral groove or slot 80 adapted to register with the port 70 in the valve chamber so as to provide for passage of fluid from the chamber 24 through the valve and into the annular chamber 50. The groove or slot 80 is preferably tapered or calibrated so that fluid may be metered gradually from the chamber 24 through the valve into the annular passage 50.

The valve 74 has a stem 82 formed integral with a piston 84 reciprocable in the chamber 34. The piston normally seats on the lands 64 of the washer 60. It is essential that this piston be of such structure as to withstand high pressures without seepage of fluid past the piston and also without injury to the component parts of the piston. The invention herein claimed relates to this particular piston and the structure heretofore described constitutes in part the environment within which this piston functions.

As shown, this piston 84 includes a head 86 having a plurality of passages 88 therethrough providing communications between the chambers 24 and 34, and a concentrically disposed shallow bore 90. A rubber washer 92 seated on the head 86 of the piston has a concentric opening therethrough registering with the shallow bore 90. This washer is preferably constructed from rubber having a high durometer reading. The diameter of the washer is slightly less than the gauge of the chamber 34, so that fluid may by-pass the washer when it is not under pressure. The washer 92 has a concaved face 94, and this concaved face in conjunction with the perimeter of the washer provided a pronounced lip 96. A spacer or pressure block 98 seated on the concaved face of the washer has a convex face 100 complementary to the concaved face of the washer. The pressure block 98 has an extension 102 concentrically disposed on its convexed face, and this extension is received by the opening in the washer and also by the bore 90 in the head of the piston with small clearance between the bottom of the bore and the free end of the extension 102, so as to limit the compressibility of the washer and thus avoid binding of the washer in the chamber 34.

The pressure block 98 has a plurality of spaced passages 104 therethrough controlled as by a sealing cup 106 seated on the pressure block. High pressure imposed on the sealing cup 106 is transmitted through the pressure block 98 to the washer 92. This results in radial expansion of the rubber washer 92, and, because of the particular contour thereof, the lip 96, when the washer is deformed under pressure, engages the wall of the chamber 34 with substantial bearing surface.

The fluid pressure device within which the piston 84 functions includes a two-way valve 108

seated within the head of the cylinder 18 within the chamber 34 and controlling the discharge port 22. A spring 110 interposed between the sealing cup 106 and the two-way valve 108 serves to retain the cup and valve against displacement and also to return the pistons 40 and 84 to their retracted positions. The spring 110 is of high elasticity, and is preferably balanced with the spring 76 in the valve chamber 68.

10 A fluid pressure delivery pipe or conduit 112 has branches connected respectively to fluid pressure actuated motors 114, preferably arranged in pairs, one pair for actuating the brakes associated with the front wheels of a vehicle, and another 15 pair associated with the rear wheels of the vehicle.

15 The brakes may be of any preferred type. As shown, each of the brakes includes a fixed support or backing plate 116, a rotatable drum 118 associated therewith, a pair of friction elements or shoes 120 pivoted on the backing plate for co-operation with the drum, a retractile spring 122 connecting the shoes, and a motor corresponding to the fluid pressure motors 114 mounted on the 20 backing plate 116 between the shoes and connected thereto for actuating the shoes into engagement with the drum against the resistance of the retractile spring.

25 A thrust pin 124 has one of its ends seated in a socket in the back of the piston 40, and on the other end of the thrust pin is a coupling 126 connected by a flexible boot 128 to the open end of the cylinder 18 for the exclusion of dust and other foreign substances. A rod 130 has one of its ends connected to the coupling 126 and its other end pivotally connected to a foot pedal lever 132 rockable on a stub shaft 134 and connected by a retractile spring 136 to a fixed support 138.

30 In a normal operation of the fluid pressure braking system, upon depressing the foot pedal lever 132 force is transmitted therefrom through the rod 130 and thrust pin 124 to the piston 40, resulting in movement of the piston 40 on its compression stroke, and also advancing the piston 84.

35 During the initial movement of the pistons 40 and 84 on the compression stroke, the sealing cup 58 on the piston 40 closes the port 28, and the sealing cup 106 on the piston 84 closes the port 38; and, thereafter, as the pistons advance, fluid in the chamber 24 is displaced therefrom through the passages 88 in the piston 84, past the washer 92, through passages 104 in the pressure block 98, and past the sealing cup 106, into the chamber 34, thence past the valve 108, through the discharge port 22 and fluid pressure delivery pipes 112, into the fluid pressure actuated motors 114, causing energization of the motors with the resultant actuation of the friction elements 120 into engagement with the drums 118 against the resistance of the retractile springs 122 to effectively retard rotation of the drums.

40 During this operation, a large volume of fluid is displaced from the chamber 24 at a comparatively low pressure to accomplish a quick movement of the friction elements into engagement with the drums, and, thereafter, as the pistons advance, the reaction force on the fluid in the system forward of the pistons increases the pressure on the fluid in the chambers 24 and 34 until a predetermined equalized pressure on the fluid in the chambers is attained.

45 From this period of operation, further advance of the pistons opposed by the reaction

forces produces a differential of pressure in the chambers 24 and 34, imposing a slightly greater pressure on the piston 84, tending to hold the piston 84 against movement; and, thereafter, relative movement of the pistons 40 and 84 gradually compresses the spring 76, resulting in cracking the valve and the metering of fluid by the valve from the chamber 24, through the calibrated passage 80 and the port 70 into the annular chamber 50, thence through the port 26 into the reservoir. The passage 80 is so calibrated that the relief of fluid in the chamber 24 is effected gradually so as to smooth out the operation.

In instances where the foot pedal lever 132 is actuated impulsively, resulting in an extremely rapid advance of the piston 40, pressure created on the fluid in the chamber 24 causes a rapid forward surge of fluid in the chamber 24 against the back of the piston 84, tending to advance the piston 84. This advance movement of the piston 84 is yieldingly resisted by the column of fluid in the system forward of the piston 84 under the load of the friction elements of the respective brake structures.

The spring 110 also yieldingly resists this movement of the piston 84. This spring is of high elasticity, hence the combined reaction forces inhibit material movement of the piston 84, and this results in flow of fluid from the chamber 24 through the passages 88 in the piston 84, past the washer 92, through the passages 104 in the pressure block 98, and past the sealing cup 106 into the chamber 34, until the pressures on the fluid in the chambers 24 and 34 are equalized at a predetermined pressure adequate to move the friction elements into engagement with the drums, and, thereafter, as the pressure on the fluid increases, the reaction forces on the piston 84 open the valve 74 against the resistance of the spring 76, as in a normal operation.

Upon conclusion of a braking operation, the foot pedal lever 132 is released, and returns to its retracted position under the influence of the retractile spring 136. This results in retraction of the rod 130 and thrust pin 124, and release of the piston 40 and return of the pistons 40 and 84 under the influence of the springs 66 and 110. During this operation, the spring 76 moves the valve 74 to its closed position.

As the pistons 40 and 84 return to their retracted positions, a partial vacuum is created in the chamber 34, and this results in drawing fluid from the reservoir 10 through the supply port 25, into the annular passage 50, thence through the passages 56 in the head of the piston 40, past the sealing cup 58 thereon, into the chamber 24, thence through the passages 88 in the piston 84, past the washer 92, through the passages 104 in the pressure block 98, and past the sealing cup 106 thereon into the chamber 34, completely filling the chambers 24 and 34.

During this operation, fluid is returning to the chamber 34 from the fluid pressure actuated motors 114, and the fluid pressure delivery pipes connecting the motors to the cylinder 18 under the influence of the retractile springs 122 connecting the friction elements of the respective brake structures. This may result in the chamber 34 receiving a quantity of fluid in excess of its capacity, and under this condition, the excessive quantity of fluid received by the chamber 34 is displaced therefrom through the port

5 38 and passage 36 into the chamber 24, thence through the port 28 into the reservoir.

A modification of the invention is illustrated in Fig. 4. In this modification the piston 140 has a head 142 provided with spaced passages 144 therethrough affording communications between chambers 146 and 148. The head also has a concentric bore 150, and seated in the bore is a spring 152. A resilient washer 154 seated on the head has a marginal lip 156 and a concentric opening 158 registering with the bore 150. This washer is preferably made of rubber, having a high durometer reading, and the diameter of the washer is slightly less than the gauge of the complementary chamber, so that fluid may normally by-pass the washer.

20 A spacer or pressure block 160 seated on the washer 154 has a face complementary to the face of the washer and a concentric extension 162 received by the opening 158 in the washer and the bore 150 in the head of the piston, and seated on the spring 152 so as to limit the compressibility of the washer to avoid binding thereof in the complementary chamber. The compression block 25 has spaced passages 164 therethrough for the passage of fluid, and seated on the pressure block is a sealing cup 166 for control of the passages through the piston and the pressure block.

25 As in the preferred embodiment of the invention, high pressure imposed on the sealing cup 30 166 is transmitted by the pressure block 160 to the washer 154, resulting in radial expansion of the washer. Due to the corresponding abutting faces of the washer and the pressure block, the 35 marginal flange or lip 156 of the washer is deformed under pressure and forced into engagement with the wall of the chamber over a substantial bearing surface, adequate to effectively seal the piston in the chamber. However, the 40 expansion of the washer is limited to a degree determined by the elasticity of the spring 154.

45 While this invention has been described in connection with certain specific embodiments, the principle involved is susceptible of numerous other applications that will readily occur to persons skilled in the art. The invention is, therefore, to be limited only as indicated by the scope of the appended claims.

I claim:

50 1. A device of the class described comprising a piston, an elastic member thereon expansible radially, means cooperating with the piston and responsive to fluid pressure to move relative to the piston for compressing the elastic member and providing for the radial expansion thereof, and sealing means supported on the elastic member.

55 2. A device of the class described comprising a piston, a compressible member thereon having a high durometer reading, a fluid pressure responsive block on the resilient member, and a sealing cup on the pressure block having a relatively low durometer reading and means in the piston resisting and limiting the movement of the pressure block.

60 3. A device of the class described comprising a piston, a compressible member thereon, a pressure block on the compressible member, means for limiting movement of the pressure block, and a sealing cup on the pressure block.

65 4. A device of the class described comprising a piston, a yieldable member thereon having a concaved face, a pressure block seated in the concaved face, said block responsive to fluid pres-

sure means for limiting movement of the pressure block, and a free floating sealing cup on the pressure block.

5. A device of the class described comprising a piston, a radially expansible washer on the piston having a concaved face, a fluid pressure responsive block seated in the washer having a convex face complementary to the concave face of the washer, means for limiting movement of the pressure block, and a flexible sealing cup on the pressure block.

6. A device of the class described comprising a cylinder element, a piston reciprocable within the cylinder having spaced passages therethrough, a radially expansible washer seated on the piston of less diameter than the cylinder bore, said washer having a concaved face, a pressure block seated on the concave face of the washer having a convexed face complementary to the concaved face of the washer responsive to fluid pressure, means for limiting movement of the pressure block, and a flexible sealing cup seated on the pressure block.

7. A device of the class described comprising a cylinder, a piston reciprocable within the cylinder, said piston having spaced passages therethrough and a concentric recess, an elastic washer on the piston having less diameter than the piston, said washer having a concaved face and a concentric opening registering with the recess, a pressure block having a convexed face complementary to and received by the concaved face on the washer, an extension on the convexed face of the pressure block received through the opening in the washer and within the recess in the piston for limited relative movement between the piston and the block, and a sealing cup on the pressure block.

8. A device of the class described comprising a piston having spaced passages therethrough and a concentric recess, an elastic washer on the piston having an opening therethrough registering with the recess, a pressure block on the washer having an extension received by the opening in the washer and the recess in the piston, a compression element between the extension and the bottom of the recess, and a sealing cup on the pressure block.

9. A device of the class described comprising a cylinder, a piston reciprocable within the cylinder and providing by-pass clearance with the cylinder wall, a radially expansible washer seated against the head of the piston and normally providing by-pass clearance with the cylinder wall, a fluid pressure responsive member seated against the washer adapted to expand the washer radially when urged axially thereagainst, and a sealing member seated against the pressure member.

10. A device of the class described comprising a cylinder, a piston reciprocable within the cylinder and providing by-pass clearance with the cylinder wall, a radially expansible washer seated against the head of the piston and normally clearing the cylindrical wall throughout its circumference and having a dished outer face, a pressure member seated against the dished face of the washer and having by-pass clearance with the cylinder wall and adapted to expand the washer radially when urged axially thereagainst, means limiting the compression of the washer by the pressure member, and a sealing member seated against the pressure member.

11. A device of the class described comprising a cylinder, a piston reciprocable therein and having a by-pass clearance with the cylinder wall, a washer seating against the head of the piston and having a normal diameter spaced from the cylinder wall, said washer being radially expansible under axial pressure to seal against the cylinder wall, and pressure sealing means seating against said washer having a portion normally sealing against the cylinder wall, said sealing means adapted to exert axial pressure on the washer to expand the same radially into sealing engagement with the cylinder wall.

12. A device of the class described comprising a cylinder, a piston reciprocable therein and having a by-pass clearance with the cylinder wall, a washer seating against the head of the piston and having a normal diameter spaced from the cylinder wall, said washer being radially expansible under axial pressure to seal against the cylinder wall, a pressure member seated against said washer having a part extending therethrough toward the piston adapted to limit the compressibility of the washer, and a sealing cup seated against said pressure member normally sealing against the cylinder wall, and means yieldingly urging said sealing cup pressure member and washer toward the head of the piston.

13. A device of the class described comprising a piston, an elastic member thereon expansible radially, a pressure member on the elastic member and a sealing member on the pressure member, said members being free floating with respect to the piston and to one another.

14. A device of the class described, comprising a piston, a yieldable member thereon, means limiting the yieldability of the member and a sealing member supported on the means, said means and members being free floating.

15. A device of the class described comprising a piston, a compressible member thereon expansible radially, a pressure block on the member solely axially movable relative to the piston having a sealing means associated therewith, said sealing means responsive to fluid pressure to actuate the pressure block and thereby compress and provide for radial expansion of the member, and means in the piston affording resistance to movement of the block.

16. A device of the class described comprising a piston, an elastic member thereon expansible radially thereto, a fluid pressure responsive block juxtaposed on the member and supported by the piston for axial movement relative thereto, and a sealing cup on the pressure block movable axially relative to the piston and expansible radially relative thereto, the block effective upon movement relative to the piston to compress the central portion of the elastic member and provide for uniform radial expansion thereof.

17. A device of the class described comprising a piston, an elastic member on the head thereof, a fluid pressure responsive block juxtaposed on the member and supported by the piston for axial movement relative thereto, the block effective upon movement toward the piston to compress the elastic member therebetween and provide for peripheral expansion of the elastic member, and a sealing means on the block.
